UNITED STATES PATENT OFFICE.

SVEND E. JOHANNESEN, OF PITTSFIELD, MASSACHUSETTS, ASSIGNOR TO GENERAL ELECTRIC COMPANY, A CORPORATION OF NEW YORK.

TRANSFORMER.

1,101,027.

Specification of Letters Patent. Patented June 23, 1914.

Application filed April 2, 1909. Serial No. 487,566.

To all whom it may concern:

Be it known that I, SVEND E. JOHANNESEN, a citizen of the United States, residing at Pittsfield, in the county of Berkshire, State 5 of Massachusetts, have invented certain new and useful Improvements in Transformers, of which the following is a specification.

My invention relates to transformers, and has for its object certain improvements in 10 the construction of such transformers to cheapen their cost of production.

The novel features of my invention will be pointed out with more particularity in the 15 claims attached to and made a part of this specification.

For a further understanding of my invention, reference may be had to the accompanying drawings, where—

Figure 1 shows a vertical view, partially 20 in section, of a transformer built in accordance with my invention; Fig. 2 shows a top view of the same, with the cover removed; and Fig. 3 shows a modification of my invention, only the more important features 25 of such modification being shown.

Referring first to Fig. 1, 1 is a casing of the transformer, which is open at the top in the usual manner, and is inclosed by a cover 2. Within the casing is placed a core 3 formed of punchings in the usual manner with the windings 4. I have shown my invention as applied to a transformer built in general accordance with the transformer construction shown in Patent No. 861,073, 30 but it will be obvious that other well known forms of construction may be used for the core and the winding. At the top and the bottom of the punchings are clamping plates 5 and 6. Surrounding certain of the 35 legs are straps 7, which are fastened together near the legs by bolts 8, for compressing the punchings or laminations together and holding these straps to the core-legs in the manner well understood by those skilled 40 in the art. At the upper end of the straps are shown bolts 9, which fasten the strap to the canopy 10, upon which canopy may be a terminal-board 10¹. The straps are shown as extending above the canopy, so that they 45 may be used for readily lifting the core windings and canopy from the casing, and thus additional lifting devices need not be employed.

Surrounding other legs of the core, I have 50 shown other straps 11, which are in general

similar to straps 7, and are fastened together above the core-legs by bolts 12, for the purposes already mentioned with reference to straps 7. These straps are shown as having their upper ends bent outwardly, so that they may be fastened by means of bolts 13 to lugs 14 formed in the casing. At the bottom of the casing is a centering boss 25, shown in dotted lines in Fig. 1, and the core is formed with a recess which is adapted to 60 inclose this boss. If desired, the centering boss may be made a part of plate 5, and a suitable recess provided for inclosing it in 65 the casing.

By the construction which I have shown, 70 the transformer core and winding are held firmly to the casing and the canopy, and at the same time the core and winding may be easily removed from the casing by loosening the bolts 13, which fasten straps 11 to the 75 casing, and lifting the movable members by straps 7.

In Fig. 3 I have shown a modification of Fig. 1, and have only illustrated the upper portion of the core, the straps 7 and a portion of the canopy 10. The modification consists in making straps 7 not only serve for compressing the punchings forming certain of the core-legs together and fastening the core to the canopy, but also in adapting 80 them to fasten the core and canopy to the casing. This is done by bending the upper portions of these straps substantially in the manner shown, so that they may be fastened by bolts 13¹ to lugs in the casing which will be 85 in general similar to lugs 14, and which are not illustrated. The straps in this modification also serve to lift the movable members from the casing. While I have shown only two straps 7, it will be obvious that I 90 may employ more straps if I so desire.

While I have shown my invention as applied to a certain particular construction with reference to a certain particular type of transformer, I do not limit myself to 100 such construction or such type of transformer, but seek in the appended claims to cover all forms of construction and types of transformers to which my invention may be applied by those skilled in the art, and which do not depart from the spirit of my 105 invention.

What I claim as new and desire to secure by Letters Patent of the United States is:

1. The combination in a transformer of a 110

casing, a canopy, a laminated core composed of a plurality of legs, and means compressing the laminations forming certain of the core legs together, fastening the canopy to the core, and fastening the core to the casing.

2. The combination in a transformer of a casing, a canopy, a laminated core composed of a plurality of legs and straps adapted to 10 compress the laminations forming certain of the core legs together, fasten the canopy to the core, and lift the core and canopy from the casing.

3. The combination in a transformer of 15 a casing, a core composed of a plurality of legs, and straps surrounding certain of the core legs, adapted to fasten the core to the casing.

4. The combination in a transformer of a 20 casing, a laminated core composed of a plurality of legs, a canopy, straps surrounding certain of the core legs, compressing the laminations forming the same together and fastening them to the canopy and to the 25 casing.

5. The combination in a transformer of a casing, a laminated core composed of a central leg surrounded by the transformer winding, and outside legs, a canopy, straps surrounding certain of the outside legs, 30 compressing the laminations forming the same together and fastening them to the canopy, and means for fastening the core and the canopy to the casing.

6. The combination in a transformer, of 35 a laminated core composed of a plurality of legs, a winding surrounding one of said legs, a strap surrounding another of said core legs on three sides thereof and a bolt passing through said strap adjacent the fourth 40 side of said leg to compress the laminations thereof.

In witness whereof, I have hereunto set my hand this thirty-first day of March, 1909.

SVEND E. JOHANNESEN.
